(57) **CLAIM**

The ornamental design for a light for a gate, as shown and described.

DESCRIPTION

FIG. 1 is a side perspective view of a light for a gate; FIG. 2 is an enlarged front perspective view thereof; FIG. 3 is an enlarged side elevational view thereof; and, FIG. 4 is an enlarged front elevational view thereof. The broken line disclosure of portions of a gate structure is intended to show environment, and forms no part of the claimed design.

1 Claim, 4 Drawing Sheets
